UNITED STATES PATENT OFFICE.

HENRY GALLAGER, OF SAVANNAH, GEORGIA, ASSIGNOR TO THE NATIONAL MALLEABLE CASTINGS COMPANY, OF CLEVELAND, OHIO, A CORPORATION OF OHIO.

COUPLING.

SPECIFICATION forming part of Letters Patent No. 775,167, dated November 15, 1904.

Application filed November 15, 1902. Serial No. 131,548. (No model.)

To all whom it may concern:

Be it known that I, HENRY GALLAGER, a resident of Savannah, in the county of Chatham and State of Georgia, have invented certain new and useful Improvements in Couplings; and I do hereby declare the following to be a full, clear, and exact description of the invention, such as will enable others skilled in the art to which it appertains to make and use the same.

My invention relates to an improved coupling, the object of the invention being to provide improvements of this character in which the knuckle can be thrown open by the locking mechanism or the latter set in the coupling-head to permit the knuckle to open and remain set until moved from such position by the knuckle in closing and then fall to its locking position.

20 A further object is to provide an improved coupling which will be strong and durable, simple and efficient in operation, and in which the parts can be readily assembled and replaced in the event of the necessity of repairs.

25 With these objects in view the invention consists in certain novel features of construction and combinations and arrangements of parts, as will be more fully hereinafter described, and pointed out in the claims.

30 In the accompanying drawings, Figure 1 is a view, partially in section, illustrating my improvements. Figs. 2, 3, and 4 are other views in section thereof, and Figs. 5, 6, and 7 are views of details of construction.

35 1 represents the coupling-head, and 2 the draw-bar, of my improved coupling, which are strengthened by external and internal ribs, as shown. The knuckle 3 is hinged between the projecting lugs 4 of the head by an ordinary

40 pin 5 and is made with a curved tailpiece 6 to enter an opening in the front of the head 1 and be locked therein by my improved locking-block 7, as will more fully hereinafter appear. The locking-block 7 is made with an

45 upwardly-projecting inclined arm 8, having a trunnion 9 at right angles thereto to enter an opening in the lower end of the uncoupling-pin 10, projecting up through a slot in the top

of the head, perforated to connect the operating mechanism and made with a shoulder or flange to rest on the top of the head and prevent the entrance of water and dirt thereinto. The trunnion 9 is made cam-shaped at its free end, and the opening in the uncoupling-pin is the same shape, normally out of alinement therewith, but which can be moved into alinement when the knuckle is removed and the block swung forward, thus permitting the parts to be readily disconnected and the block removed through the open front of the coupling-head.

The locking-block in its locking position rests in a recess 11 in the bottom of the coupling-head and is made with a curved tongue or finger 12, which projects down through an opening *a* in the bottom of the head. The inclined arm 8 at the top of block 7 is adapted when the block is raised by the pin 10 to fulcrum on an internal shoulder or enlargement 13 in the upper portion of head 1 and throw the tongue or finger 12 outward, and as it engages the inner face of the tail of the knuckle it will force the knuckle to its open position. This tongue or finger 12 is at one side of and made narrower than the block, and to insure its engagement with the knuckle-tail it is enlarged on one side at or near its lower end, as shown at 14, which projects sufficiently to one side of the tongue or finger to contact with the knuckle-tail and give it its opening movement.

The pivotal point of the locking-block with pin 10 is in advance of the center of gravity thereof, so that when the block is raised to a position to permit the knuckle to unlock the tongue or finger 12 will be thrown slightly forward far enough to move from above the opening *a* in the bottom of the head and rest on the bottom at the edge of said opening. The tail of the knuckle is provided at its end, on its upper face, with an enlargement 15, inclined downward to the end of the knuckle-tail, so as to ride beneath the locking-block, elevating it and permitting it to fall to its set position, but which in closing strikes the block and pushes it back from its set position and the

tongue or finger 12 over the opening in the head, compelling it to fall therein and the block to fall to its locked position when the tail has freed it. This enlargement 15 has an abrupt wall forming a shoulder which strikes a depending flange or wall 15^a in the coupling-head when the knuckle is closed, thus limiting the closing movement of the knuckle and preventing the tail from striking the wall of the head, which might and probably would break the same, as the knuckles are closed with great force in coupling cars.

The block, as before stated, in its locking position rests in a recess in the bottom of the coupling-head, and it is provided on its bottom at one side with an inclined or beveled projection 16, which rests in a deeper recess 17, the rear wall of which inclines and forms a slide or guide 18, which serves to guide the block to its locking position when forced backward by the knuckle-tail in closing.

In order to insure a sufficient force to the inward movement of the knuckle-tail to compel the locking mechanism to properly act, a small shoulder or enlargement 18^a is provided on the lower face of the knuckle-tail, which strikes the coupling-head, and the knuckle-tail must be closed with sufficient force to raise the shoulder over the edge of the coupling-head, and thus engage the locking-block with such force as to compel it to correctly act.

The side of the coupling-head adjacent to the block 7 is enlarged and flat, as shown at 20, to prevent lateral movement of the block 35 and serve as a guide therefor.

The operation of my improvements is as follows: With the parts shown in Fig. 1 the coupling is securely locked, as the block 7 rests against the flat side face of the coupling-head and in front of the end of the knuckle-tail. To open the knuckle, the pin 10 is raised, thus elevating block 7 above the knuckle-tail and lifting the tongue or finger 12 out of the opening *a* in the bottom of coupling-head 1.

When the block 7 moves far enough upward, its inclined arm 8 will strike shoulder 13 and fulcrum thereon, and the further lifting strain on the pin 10 will force tongue or finger 12 forward and against the rear face of the knuckle-tail and move the knuckle to its open position. When the knuckle-tail is closed in the act of coupling, it engages and forces backward the locking-block until the finger 12 drops into the opening *a*. Upon its 55 further movement the knuckle-tail then frees the locking-block, which latter then moves forward, guided by the incline 18, into its locking position in front of the tail of the knuckle. To set the locking mechanism to

60 permit the knuckle to open, the pin 10 is drawn upward, elevating block 7 and tongue or finger 12 until the latter is free of the opening in the bottom of the coupling-head, when, owing to the fact that the preponderance of 65 weight of block 7 and tongue 12 are on one

side of the pivotal point, the tongue will swing forward and rest on the recessed bottom of the head, holding the block out of its locking position. When the knuckle is opened, the beveled enlargement 15 on the 70 knuckle-tail engages the lower face of the block and elevates it slightly, permitting it to fall back to its set position; but when the knuckle is closed the enlargement 15 will strike the block and force it back until the 75 tongue 12 falls into the opening, the knuckle-tail continuing to force back the block until it is in its closed position, when it frees the block and incline 18 compels it to immediately fall forward to its locking position. 80

It will be seen that with my improvements I can throw the knuckle open, set the lock to permit it to open, and automatically lock when the knuckle is closed regardless of the position of the locking-block, for if it is in 85 its locking position the knuckle-tail will force it back up incline 18 until the tail is in its closed position, when the block will slide forward and lock it in such position.

A great many changes might be made in 90 the general form and arrangement of the parts described without departing from my invention, and hence I would have it understood that I do not confine myself to the precise details set forth, but consider myself at 95 liberty to make such changes and alterations as fairly fall within the spirit and scope of my invention.

Having fully described my invention, what I claim as new, and desire to secure by Letters 100 Patent, is—

1. In a coupling, the combination with the tail of a pivoted knuckle, of a tilting or tipping locking-block provided with a depending member adapted to swing forwardly and support the locking-block when raised to its unlocked position, said member having a lateral enlargement adapted to open the knuckle, substantially as set forth. 105

2. In a coupling, the combination with the tail of a pivoted knuckle, of a tilting or tipping locking-block provided with a depending member having a lateral enlargement, said block being constructed so that when raised it will tilt and seat its depending member on a support and retain the locking-block in its unlocked position, and when raised still higher the lug on said depending member will operate as a lever and open the knuckle, substantially as set forth. 115 120

3. In a coupling, the combination with the tail of a swinging or pivoted knuckle having a cam-surface on its forward end, of a tilting or tipping locking-block provided with a depending tongue or finger located on one side of the block, the parts being constructed to cause the tongue or finger to move forward and seat itself on the lower wall of the coupling-head, when the locking-block is raised to its unlocked position, and cause the cam-surface 130

face on the knuckle when the latter is swung open, to lift and tilt the block and move its supporting-finger forwardly and into the path of movement of the knuckle, substantially as set forth.

4. In a coupling, the combination with the tail of a swinging knuckle having a raised cam-surface on its upper surface at its forward end, of a tilting locking-block constructed with a rearward projection at its upper end which is adapted to engage the wall of the coupling-head, and provided with a finger located on one side of the block, which serves to support the block in its unlocked position and also engages the tail of the knuckle and throws it into its open position, substantially as set forth.

5. In a coupling, the combination with a coupling-head, a knuckle pivoted thereto and a tail on the knuckle projecting into the head, of a locking-block to lock the tail in the head, a beveled enlargement on the bottom of said block, and an inclined guide for said enlargement to compel the block to move forward to its locking position when forced backward therefrom.

6. In a coupling, the combination with a head, a pivoted knuckle and a tail thereon to enter the head, of a locking-block, a curved tongue or finger adapted to eject the tail when the block is elevated and tilted, and adapted to rest on the bottom of the coupling-head and hold the block out of its locked position, and a beveled enlargement on the knuckle-tail to ride beneath the block in opening but force it from its set position in closing, and also limit the closing movement of the knuckle.

7. In a coupling the combination with a pivoted knuckle, and a tail thereon to enter the head, of locking mechanism in the head, and a shoulder or enlargement on the bottom of said tail to strike the edge of the open front

of the head and compel the employment of some slight force to cause the knuckle-tail to enter the cavity of the draw-head.

8. In a coupling, the combination with the tail of a swinging knuckle having a raised cam-surface on its forward end, of a tilting locking-block provided with a depending finger on one side thereof, and adapted to support the locking-block in its unlocked position, said block being constructed with an inclined surface on its under side with which the raised cam-surface on the tail of the knuckle engages, when the latter is swung open and operates to raise the block and move it forwardly into the path of movement of the tail of the knuckle, substantially as set forth.

9. In a coupling, the combination with a vertically-movable pin or link and a locking-block, one of said parts being provided with an elongated hole, and the other with a trunnion having an elongated head thereon adapted to enter the elongated hole in the other member and to be locked against accidental displacement when the parts are in their operative positions, substantially as set forth.

10. In a coupling, the combination with a vertically-movable pin or link having an elongated hole in its lower end, of a locking-block provided with a pivotal bearing having an elongated head on its outer end which is adapted to enter the elongated hole in pin or link and lock the block against accidental displacement.

In testimony whereof I have signed this specification in the presence of two subscribing witnesses.
